US00D976333S

(12) **United States Design Patent** (10) Patent No.: **US D976,333 S**
Chen et al. (45) Date of Patent: **** Jan. 24, 2023**

(54) **SCOOTER**

(71) Applicant: **Zhejiang Well Shine Industry & Trade Co., Ltd.**, Jinhua (CN)

(72) Inventors: **Xi Chen**, Jinhua (CN); **Fei Tang**, Jinhua (CN); **Liang Zhou**, Jinhua (CN); **Basheer Feroz**, Jinhua (CN); **Guixian Ji**, Jinhua (CN)

(73) Assignee: **ZHEJIANG WELL SHINE INDUSTRY & TRADE CO., LTD.**, Jinhua (CN)

(**) Term: **15 Years**

(21) Appl. No.: **29/781,937**

(22) Filed: **May 3, 2021**

(30) **Foreign Application Priority Data**

Nov. 3, 2020 (CN) 202030658868.7

(51) **LOC (14) Cl.** **12-11**

(52) **U.S. Cl.**

USPC **D21/423**

(58) **Field of Classification Search**

USPC D12/107, 110-112; D21/423, 424, 426, D21/435, 533, 760, 765, 771
